UNITED STATES PATENT OFFICE.

EMANUEL C. GIPE, OF CHICAGO, ILLINOIS.

STORE-SERVICE APPARATUS.

SPECIFICATION forming part of Letters Patent No. 760,735, dated May 24, 1904.

Application filed November 20, 1903, Serial No. 181,990. (No model.)

To all whom it may concern:

Be it known that I, EMANUEL C. GIPE, of Chicago, in the county of Cook and State of Illinois, have invented certain new and useful 5 Improvements in Store-Service Apparatus, of which the following is a description, reference being had to the accompanying drawings, forming a part of this specification, in which corresponding numerals of reference in the 10 different figures indicate like parts.

My invention relates to apparatus for propelling and conveying cash and package carriers either upon horizontal or grade lines; and one of the more important objects of my 15 invention is to so utilize what is commonly known as the "spread-wire" system as to provide for the maximum spread of said wires at the transmitting end when forwarding the carrier, coupled with the maximum exercise 20 of propelling power, while causing them to assume a substantially parallel relation as soon as the manual impulse which separates them ceases, thereby enabling the carrier to be returned by gravity to the sending station should 25 it fail to reach its destination.

A further object is to provide means particularly applicable to grade-lines for enabling the wires at the receiving station to be kept close together while being moved in opposite directions to conform to the movement 30 of the lever mechanism at the sending station.

A still further object is to provide improved automatic catch mechanism adapted to provide for the lateral sway of the car.

Other objects are to so arrange and combine the lever mechanism as to enable the lines to be lower than heretofore, as well as to anchor the wires in such a way as to enable them to maintain proper alignment with the 40 actuating mechanism.

To these ends my invention consists in the combination of elements hereinafter more particularly described, and definitely pointed out in the claims.

In the drawings, Figure 1 is a side elevation of a grade-line embodying the features of my invention, the parts being shown as they would appear when the carrier is at the receiving or cashier's station. Fig. 2 is an alike 45 view showing the several parts as they would

appear just before the carrier reaches the cashier's station and before the transmitting-lever is released by the operator. Fig. 3 is a sectional view in plan, taken upon the line 3, Fig. 2, in conjunction with a side view of the 55 lower end of the hanger. Fig. 4 is an enlarged plan view of the stop mechanism, showing a car about to engage therewith. Fig. 5 is a side view thereof in which the stop mechanism is shown in vertical section. Fig. 6 is 60 a side elevation of a carrier-line, showing a modified construction applicable more particularly to horizontal lines. Fig. 7 is a side elevation of a modified form of transmitting mechanism; and Figs. 8 to 12, inclusive, are 65 views showing variously-modified means for holding the wires at the receiving end of the line in parallel relation while they are being moved in opposite directions.

Referring to the drawings, 1, Figs. 1 and 2, 70 represents the usual hanger depending from the ceiling for the support of the wires at the salesman's end of the line, while 2 represents a similar but shorter hanger located at the cashier's station, which is usually elevated 75 above the level of that of the salesman.

Tapped into the lower end of the hanger 1 is a plug 3, Fig. 3, provided with laterally-extended lugs 4. A hollow fitting (generally designated by 5) is cored to receive the plug 80 3 and is provided with notches 6 to receive the lugs 4, the latter being turned in such a way that when the fitting is placed upon said plug and turned in its normal direction it will be held in place by the lugs 4 while swiveled upon 85 said plug. A clevis 7, Figs. 1 and 2, is attached to a lug upon the rear of said fitting and in turn connected in the usual way with a brace rod or wire 8. An arm 9 is rigidly formed upon said fitting and extended upwardly in such a manner as to permit it to bear against the hanger 1, said arm being notched at the upper end to receive said 90 hanger. Said fitting is provided with forwardly and downwardly extended parallel 95 arms 10, with which the lower portion of the arm 9 is connected. A suitable bolt is passed through a bore in said arms at 11, upon which is pivotally mounted a lever 12, the upper end of which is connected by means of a clevis 13,

100

to a carrier-wire 14. A coiled spring 15 tends to maintain the lever 12 in a normal position, as shown in Fig. 1. To the lower end of the lever 12 is pivotally connected a handle-bar 16, the forward end of which is jointedly connected, by means of a clevis 17, to the lower carrier-wire 18 of the line. Upon the lower part of the bar 16, at the forward end thereof, is an integral depending portion 19, upon the rear end of which is formed a rigid handle 20, while the forward part is provided with laterally-extended lugs 21 upon opposite sides thereof through bores in which are loosely extended parallel rods 22, having coiled springs 23 24, respectively, mounted thereon upon opposite sides of the lugs 21. To the forward end of said rods is rigidly attached a buffer-frame 25, having vertically-pivoted jaws 26 held in normal engaging positions by means of springs 27, the whole forming a cushioned automatic stop adapted to engage the car and hold and release the same in the manner hereinafter described.

To the lower end of the hanger 2, Figs. 1 and 2, is attached a fitting 28, which in turn is anchored to any suitable support by means of a clevis 29 and wire 30. A horizontal bar 31 is secured to the fitting 28 and to a similar fitting attached to a corresponding hanger 30 and intended to serve in the usual way as a support for a series of lines converging from the various sales-stations to the cashier's desk. To a coupling 32, bolted, as shown, to the bar 31, is jointedly connected a clevis 33, to which in turn is jointedly attached at 34 a yoke 35. Pivoted at 36 to the upper extremity of said yoke is an elbow-lever 37, to one arm of which is attached a clevis 38, which serves as a connection for the upper end of the inclined carrier-wire 14. A like elbow-lever 39 is pivoted at 40 to the lower extremity of said yoke, one arm of which lever is attached, by means of a clevis 41, to the carrier-wire 18. The short arms of the levers 37 39 are jointedly connected to each other by means of a link 42, bent, as shown, in order to avoid interference with the coacting parts in their operation.

Set-screws 43, tapped into lugs of the clevis 33 above and below the pivotal point 34, serve to adjustably secure the yoke 35 in a stationary position in order to equalize the tension of the wires 14 and 18. For example, when the lever 12 and handle-bar 16 are parallel, as shown in Fig. 1, said yoke may be adjusted 55 by means of the set-screws until the tension upon the two wires is uniform. The advantage of this feature may readily be seen by studying the operation of the mechanism.

Mounted upon the wire 14 is a car 44, having upper wheels 45 and lower wheels 46, as is usual in cars of this type, one pair being mounted above the wire 14 and the other pair below the wire 18.

The yoke 35 is formed from two parallel 65 plates or bars between which the bent levers

37 39 are pivoted. Upon the lower arms of said yoke are parallel extensions 47, (shown in Figs. 1 and 2 and in enlarged detail in Figs. 4 and 5,) upon the end of which is pivoted at 48 a U-shaped frame 49, having a handle 50 extending downwardly therefrom. A spring 51, mounted upon the pivot-pin, together with an auxiliary spring 52, Fig. 5, interposed between the handle-supporting arm and a lug 53 upon the part 47, serves to maintain the frame 49 in alinement with the part 47. Stops or lugs 54, Fig. 4, serve to limit the downward movement of the rear end of the frame 49. Formed upon the opposite sides of said frame and extending laterally therefrom are extensions 21, through parallel bores in which are loosely projected buffer-rods 22 22, having coiled springs 23 and 24 24, respectively, mounted upon opposite sides of the parts 21. Pins 59 59, together with suitable collars or rings, as shown, serve to retain the spring 24 in place. The opposite ends of the rods 22 are rigidly attached to a frame 25, and inasmuch as the frame, lateral extensions, and springs correspond in every respect to those heretofore referred to in Figs. 1 and 2 I have to avoid confusion given them like numbers. Said frame is U-shaped and open at the front, as shown in Fig. 4. Pivotedly mounted in vertical axes upon the forward ends of said frame are the metal jaws 26 26, heretofore referred to, held normally in the positions shown in Fig. 4 by means of the springs 27, mounted upon the axes thereof. Stops 60 60 upon said jaws are arranged to engage lugs 61 61 upon the frame 25 to limit the movement of the jaws 26 against the action of said springs. The jaws are provided with facings 62, of leather, while a leather facing 63 is rigidly attached to the inner face of the frame 25.

Upon each end of the car 44 is formed a rounded head or catch 64, having shoulders 65 in the rear thereof, as shown in Fig. 4.

The operation of said device is as follows: Assuming the car to be in the position shown in Fig. 1, in which position it is held by the stop mechanism, the catch 64 being in engagement with the jaws 26, which engage the shoulders 65, the car is released by pulling downwardly upon the handle 50, thereby tilting the frame 49 upon the pivot 48, Figs. 4 and 5, and thus drawing the jaws out of engagement with said catch. The wires 14 and 18 being substantially parallel and upon an incline, the car is free to travel by gravity to the other end of the line. The handle-bar 16 being parallel with the lever 12, the stop upon the former is in position to receive and engage the catch 64 of the car in the following manner: The rounded portion of the catch is caused to strike the cushions 62 of the jaws 26, thereby separating them against the action of the springs 27 and allowing said head to abut against the leather facing 63, Fig. 4, of the frame 25, the impact of which is cushioned.

ioned by the springs 23, which are compressed thereby. The recoil of said springs tends to throw the car back; but the shoulders 65 being in engagement with the jaws, or rather with the ends of the leather facings thereon, the catch is securely held in place, while the rebound of the car is cushioned by the action of the springs 24. The converging jaws perform an important and novel function in my device, inasmuch as they insure a positive and certain engagement of the catch therewith notwithstanding the lateral swing of the car. Should the car swing laterally, so as to cause the catch to strike only one of the jaws, the latter will be swung back thereby, and before the rebound of the car can occur, so as to free it from engagement, the spring 27 of the jaw will have pushed the said head laterally against the companion jaw, when said jaws, acting in conjunction, will cause the car to be moved into proper alinement and to remain in a vertical position.

In propelling the car from the salesman's station up the grade to that of the cashier the operator grasps the handle 20 and pulls the handle-bar 16 downwardly against the action of the spring 15, as shown in Fig. 2. The first part of this movement serves to draw the jaws 26 downwardly to release the car. It will be noticed that this action causes the maximum stress to be imparted to the lower wire, thereby greatly increasing the propelling action thereof as compared with former constructions, in which the lower wire exerts no positive propelling action, while at the same time causing the upper wire to be raised, as heretofore. As a result of this increased propelling power I am enabled to shorten the length of the lever 12 for a given length of line, while increasing the propulsive force which may be applied to the car. At the same time the action of the compound lever system at the receiving end is such as to cause the two wires to remain substantially parallel or very close together while moving in opposite directions.

While I prefer the construction shown in Figs. 1 and 2 for grade-lines, either for package or cash carriers, upon horizontal lines where it is necessary to propel the car in both directions I would recommend the adoption of corresponding propelling mechanism at both ends. Such a construction is shown in Fig. 6, in which the fitting 5, lever 12, and link 16 are duplicated. In this construction, however, it is essential that the levers 12 should be disposed substantially at right angles with respect to each other—that is to say, when the one is vertical the other should be horizontal.

In Fig. 7 I have shown a modification of the propelling mechanism, in which a fitting 66, which is a modification of the fitting 5, is secured to the hanger. A lever 67 is pivoted thereto at 68, one end of which is connected

with the wire 14. A bar 69 is pivotally attached at 70 to the other end of the lever 67. The long arm of the bar 69 is connected with the wire 18 in the manner shown, while the end of the short arm is bent upwardly and 70 jointedly connected at 71 to a link 72, which is in turn connected at 73 to an arm 74, extending rearwardly from the hanger 66. A pull-cord 75 and handle 76 enables the bar 69 to be actuated. The length of the link 72 is 75 less than the distance between the pivotal points 68 and 70. This enables the long end of the bar 69 to descend with greater rapidity than the other, thereby increasing the spread of the propelling-wires and imparting a positive initial stress directly to the lower wire in substantially the same way as is accomplished by the constructions first described. 80.

I do not confine myself to any specific means for producing a reverse longitudinal movement of the wires 14 and 18 while maintaining a parallel or substantially parallel relation between them, inasmuch as such a result may be accomplished in various ways, and in Figs. 8 to 12, inclusive, I have shown examples of 90 such varying means.

In Fig. 8 a bar 77, having grooves 78 in its upper and lower faces, respectively, as indicated in dotted lines, has one end 79 jointedly attached to a support, while at 80, upon the 95 opposite end, is a pivoted lever 81, having links 82 83 attached to its opposite ends. A friction-roller 84 is mounted upon the free end of the link 82 and arranged to run in the upper groove 78, said link being also connected 100 by means of a long clevis 85 to the wire 14. A like friction-roller 86 is mounted on the free end of the link 83 to run in the lower groove 78, said link being connected in like manner by means of a clevis 87 to the wire 105 18. The operation of the propelling mechanism at the opposite end of the line serves to actuate the wires in opposite directions, while the mechanism described preserves their parallelism. 110

In Fig. 9 a lever-support 88 is connected at 89 to a stationary point, while pivoted thereon at 90 is a lever 91, the lower end of which is connected, as shown, with the wire 18, while the upper end is connected, by means of a link 115 92, to a point 93 upon a lever 94, the upper end of which is connected at 95 to the forward end of the lever-support 88 and the lower end to the wire 14. Said levers are so proportioned and connected as to enable said wires 120 to move back and forth in the desired manner.

Fig. 10 is intended to illustrate an equivalent mechanism consisting of parallel supporting-bars 96, but one of which is shown, jointedly connected at 97 to a stationary support and having two sprocket-wheels 98 99 mounted therein. A sprocket-chain 100 is trained around the former and under the latter, which acts as an idler, and has its ends attached, respectively, to the wires 14 and 18. 130

This construction and arrangement causes the idler to press down upon the chain and to take up any slack which might occur as a result of manipulating the wires.

5 Fig. 11 shows a frame 101 adapted to be jointedly connected at 102 to a stationary support. Rack-bars 103 104 are mounted in parallel guideways in the bottom and top of said frame and are arranged, respectively, to bear 10 against friction-rollers 105 106, while the teeth thereon engage with those of a gear-wheel 107, journaled in the frame between them. Said bars are connected, respectively, with the wires 14 and 18, and when the latter are actuated 15 said bars are moved in opposite directions.

Fig. 12 shows an inclined support 108 adapted to be pivotally connected at 109 to a stationary point. Pivoted to said support at 110 and 111, respectively, are intermeshing segmental gears 112 113, having depending arms 114 115, the former of which is connected to the wire 14 and the latter to the wire 18. The connected gears cause the arms 114 115 to move in conformity with the wires, while the 20 inclined support insures uniformity of tension.

One of the advantages of my improved device in connection with cash-carrier service is that when the carrier reaches its destination at the cashier's station it cannot be returned 30 except by the action of an attendant at that end, thus preventing theft by the salesman, who might in the event of receiving even change from the customer withdraw the car in the case of the absence of the cashier and 35 keep the money without being detected. A further and pronounced advantage is that by utilizing the actuating-bar, which I have referred to as the "handle-bar," to spread the wires and actuate the swinging lever not only 40 is the power increased as stated, but I have discovered and demonstrated in actual practice that with a given manual impulse the car may be propelled with double the rapidity that it would be were the handle-bar dispensed with 45 and the lower wire attached to the lower end of the swinging lever, as has been the practice heretofore. Moreover, in such former construction the lower arm of the swinging lever is lengthened to form a handle to actuate such lever. This necessitates the raising of the lines to such a degree as to compel the use of steps to enable the operator to reach the car; otherwise the reversal of the wires from the opposite end, and the consequent rapid movement 55 of said handle, may cause it to strike a person standing beneath. My improvement avoids such danger, enables the lines to be lowered to such an extent as to render the car easily accessible, while the movement of the handle-bar is easier and more natural than is that of the lever. In addition to these considerations 60 the construction is simplified in that it enables a stop and releasing mechanism to be combined in one and placed upon the handle-bar,

the movement of which latter serves both to 65 release and to propel the car.

Having thus described my invention, I claim—

1. In a store-service apparatus, the combination of a track or way, consisting of double 70 wires, one above the other, a carrier having opposing wheels arranged to engage said wires respectively, mechanism for positively separating said wires consisting of a swinging lever pivoted between its ends to a stationary 75 support with one end jointedly connected to one of said wires, a bar jointedly connected at one end to the opposite end of said lever while the other end of said bar is attached to the second of said double wires, and means for 80 applying power directly to said bar to force its forward end away from the forward end of said lever, whereby said wires may be separated with an equally positive initial propelling action in their contact with the opposing 85 wheels as distinguished from such an action by one wire only.

2. In a store-service apparatus, the combination of a way consisting of double wires, one above the other, a carrier having opposing 90 wheels arranged to engage said wires respectively, means for positively separating said wires consisting of a lever pivoted between its ends to a stationary support with its upper end jointedly connected to one of said 95 wires, a bar jointedly connected at one end to the opposite end of said lever while the other end of said bar is attached to said secondary wire and a handle upon the forward end of said bar for positively actuating both said bar 100 and lever.

3. In a store-service apparatus, the combination of a way, consisting of double wires, one above the other, a carrier having opposing 105 wheels arranged to engage said wires respectively, means for positively separating said wires consisting of a lever pivoted between its ends to a stationary support with its upper end jointedly connected to one of said wires, a bar jointedly connected at one end to 110 the opposite end of said lever while the other end of said bar is attached to said secondary wire, a spring for maintaining said lever and bar in normal parallelism, and a handle upon the forward end of said bar for positively actuating both said bar and lever.

4. In a store-service apparatus, the combination of a track or way consisting of double wires, one above the other, a carrier having opposing wheels arranged to engage said wires respectively, mechanism for positively separating said wires consisting of a swinging lever pivoted between its ends to a stationary support, with one end jointedly connected to one of said wires, a bar jointedly connected 120 at one end to the opposite end of said lever while the other end of said bar is attached to the second of said double wires, means for

5 applying power directly to said bar to force its forward end away from the forward end of said lever, and a combined automatic stop and locking mechanism mounted upon said bar for engaging and locking said car when the bar is in its normal position, and for releasing the car when the bar is depressed.

5. In a store-service apparatus, the combination of a track or way consisting of double 10 wires, one above the other, a carrier having opposing wheels arranged to engage said wires respectively, mechanism for positively separating said wires consisting of a swinging lever pivoted between its ends to a stationary 15 support, with one end jointedly connected to one of said wires, a bar jointedly connected at one end to the opposite end of said lever while the other end of said bar is attached to the second of said double wires, means for 20 applying power directly to said bar to force its forward end away from the forward end of said lever and a combined automatic stop and locking mechanism mounted upon said bar for engaging and locking said car, when 25 said bar is in its normal position, said locking mechanism consisting of converging spring-actuated jaws having vertical axes, said jaws being mounted in an open frame whereby the movement of said frame in a vertical plane 30 may serve to withdraw them from engagement with the car.

6. In a store-service apparatus, the combination of a track or way consisting of double wires, one above the other, a carrier having 35 opposing wheels arranged to engage said wires respectively, mechanism for positively separating said wires consisting of a swinging lever pivoted between its ends to a stationary support, with one end jointedly connected to one of said wires, a bar, one end of which is jointedly connected to the opposite end of said lever while the other end is attached to the second of said double wires, means for 40 applying power directly to said bar to force its forward end away from the forward end of said lever, means for yieldingly maintaining said bar in a normal position, and a combined automatic stop and locking mechanism mounted upon said bar for engaging and locking 45 said car when said bar is in its normal position, said locking mechanism consisting of converging spring-actuated wings or jaws having vertical axes, said wings being mounted in an open frame whereby the movement 50 of said bar from its normal position will serve to withdraw said wings from contact with said car without any movement of the former upon their axes.

7. In a device of the class described, the combination of a way consisting of double wires, a carrier provided with wheels above and below said wires, mechanism for spreading said wires comprising a swinging lever having its upper end jointedly connected to the upper

wire, an actuating-bar, one end of which is 65 jointedly connected to the lower end of said lever while the other is connected in like manner to the lower wire, means for normally maintaining parallelism between said actuating-bar and lever, means for manually actuating said 70 bar to swing said lever upon its pivot to forcibly depress the lower and lift the upper wire, a catch upon said car and a locking mechanism for engaging said catch when the bar is raised and for releasing the same when the bar is 75 lowered.

8. In a store-service apparatus, the combination of a way consisting of double wires, a car mounted thereon having wheels above and below said wires, a pivoted lever having one 80 end connected to an actuating-bar, means for jointedly connecting one of said wires to the opposite end of said lever and the other to the opposite end of said bar, a spring for normally holding said bar and lever substantially parallel to each other, means for manually actuating said bar to tilt said lever while positively depressing said lower wire, and means for constantly maintaining said wires in close proximity to each other at the opposite end of the 85 way while permitting them to move longitudinally in opposite directions.

9. In a store-service apparatus, the combination of a way consisting of double wires for connecting the stations, a carrier having 90 wheels above and below said wires, mechanism for spreading said wires consisting of a swinging lever having its upper end jointedly connected to the upper wire, an actuating-bar, one end of which is jointedly connected to the 100 lower end of said lever while the other is attached to said lower wire, means for manually actuating said bar to forcibly depress the lower wire, means for returning it to a normal position, and an automatic stop and locking mechanism mounted upon said bar arranged to engage and hold said car when the bar is raised and to be released from the car 105 when the bar is depressed.

10. In a store-service apparatus, the combination of a way consisting of double wires, a carrier having wheels above and below said wires, mechanism for spreading said wires consisting of a swinging lever having its upper end jointedly connected to the upper wire, 110 an actuating-bar having one end connected to the lower end of said lever while the other end is attached to the lower wire, means for manually actuating said bar, and means in operative connection with said wires at the other 115 end of the way for holding said wires in close proximity to each other while permitting a substantially parallel longitudinal movement 120 thereof in opposite directions.

11. In a store-service apparatus, the combination of a way consisting of double wires, a carrier having wheels above and below said wires, mechanism for spreading said wires

comprising a swinging lever having its upper end jointedly connected to the upper wire, an actuating-bar having one end jointedly connected to the lower end of said lever while the other end is attached in like manner to that of the lower wire, and means for maintaining a substantial parallelism between said wires throughout their length at all times except during the act of propulsion.

12. In a store-service apparatus, the combination of a way, comprising double wires, a carrier having wheels above and below said wires, mechanism for spreading said wires comprising a swinging lever having its upper end jointedly connected to the upper wire, an actuating-bar having one end jointedly connected to the lower end of said lever while the other end is attached in like manner to that of the lower wire, means for returning said bar into substantial parallelism with said lever after the two are separated in the act of propulsion, a supporting-yoke at the opposite end of the way, bent levers pivotally mounted thereon, a link for connecting an arm of one lever with a corresponding arm of the other lever and means for connecting the opposite arm to said wires respectively.

13. In a store-service apparatus the combination of a wireway, a stationary hanger and a fitting swiveled to the lower ends of said hanger for the support of the wireway and actuating mechanism, said fitting being provided with an upwardly-projecting arm arranged to bear against said hanger, whereby the tension of the wire may cause the

proper alinement therewith of said actuating mechanism.

14. In a store-service apparatus, the combination of a wireway, a car having a catch thereon, a stop having spring-controlled leaves or jaws arranged to swing upon vertical axes and set normally at converging angles with respect to each other whereby the engagement of the catch may be insured irrespective of the lateral swing of the car, and means for removing said jaws with their supporting-frame from said catch without opening the jaws.

15. In a store-service apparatus, the combination with a car having a catch thereon, of a stop mechanism, a spring-controlled buffer for supporting said stop mechanism, U-shaped arms arranged in a horizontal plane, wings or jaws mounted in vertical axes upon the ends of said arms, said jaws being projected inwardly in converging planes, stops for limiting the movement of said jaws, springs for holding them in normal positions respectively, and means for moving said jaws with their supporting-frame away from said catch.

In testimony whereof I have signed this specification, in the presence of two subscribing witnesses, this 17th day of November, 1903.

EMANUEL C. GIPE.
